UNITED STATES PATENT OFFICE.

LOUIS E. F. WACHTER, OF NEW YORK, N. Y.

WATERPROOF WATCH-BAG.

1,247,754.

Specification of Letters Patent. Patented Nov. 27, 1917.

Application filed March 5, 1915. Serial No. 12,312.

To all whom it may concern:

Be it known that I, LOUIS E. F. WACHTER, a citizen of the United States, and a resident of New York city, county and State of New York, have invented certain new and useful Improvements in Waterproof Watch-Bags, of which the following is a specification, reference being had to the drawings herein referred to, which are made a part hereof.

My invention has for its object the production of an article of manufacture effective for its purpose, and cheap, constituting an outer casing into which a watch may be slipped and protected against water and even against moisture, and at the same time can be secured to the wrist or can be otherwise attached as required.

To this end I employ a specially formed rubber case or bag with an opening through which the watch can be inserted, and which will completely inclose the watch, pendant and bow, with the exception of a small orifice over the face of the watch. The opening leaves the hands visible through the crystal, and at the same time the edge of the opening is so made as to fit tight on the crystal forming a water-tight joint.

Specific embodiments of my invention are shown in the accompanying drawings, in which:

Figure 1 is a front view of the bag with watch.

Fig. 2 is a back view of the bag.

Fig. 3 is an edge view of the bag with part of a wrist strap inserted in loops.

Fig. 4 is a section at 4—4, through Fig. 2.

Fig. 5 is a view of a reinforcement adapted to be cemented or vulcanized to the main portion of the bag.

Fig. 6 is a section on line 6—6 of the reinforcement shown in Fig. 5.

Fig. 7 is a front view of the bag and watch with modified attaching means on the sides for wrist watch chain.

Fig. 8 is a front view of wrist watch bag and strap.

In the drawings, A is the main body of the bag preferably made of thin Pará rubber sheeting; B is a projection at one side to accommodate the pendant and bow of a

watch; C is the reinforcement around the edge; D—D are the figures, molding or printing on the rubber sheeting A; E is the opening in one side of the bag through which the hands of the watch remain visible and around the periphery of which the figures D are located, having the same relation to the projection B, as the figures on the watch form with respect to the position of the pendant; F—F are loops or straps cemented to the body of the bag A to form loops; G is a beaded or thickened or reinforced edge forming the periphery of the opening E.

In Fig. 7, H—H are two lateral extensions cemented to the bag to inclose the lateral connections on a wrist watch having a chain attached to both sides; J—J is a wrist watch chain projecting through an opening in the end of H.

In Fig. 3, K is part of a strap for a wrist watch passing through one loop F and through a specially arranged loop F', which is attached to the projection B of the bag.

In Fig. 8, K' is a strap attached transversely to the back of the bag.

In the particular embodiments of my invention, the bag or case A is formed of thin rubber sheeting of sizes slightly less than the standard sizes of watch cases, generally formed to the shape of a case with the added projection B at one side, sufficiently large to inclose the pendant, crown and bow. The opening is left on one side, the front, and the edge of the material around the opening is fashioned preferably with a thickened, tough beading G, which, however, must still be sufficiently flexible to permit the watch being inserted and then return to its minimum size, with sufficient elasticity so that it will contract snugly onto the surface of the crystal. This periphery may also be molded with a thin edge normally so positioned that it will most effectively cling to the crystal surface. The strips F—F are cemented or molded to the bag and form loops through which a wrist strap may be passed.

In Figs. 1 and 2, the bag shown has a hole through the extension B, beyond the limit of the bow, and where the two sides of the

body portion are cemented together, thereby forming a loop to attach any chain or other holding device when it is not desired to use the wrist strap.

In Fig. 8, the loop F' is placed at the back of the extension B so that the wrist strap K, passing through that loop and also loop F affords a secure connection. Loops F, as preferably made of reinforced or toughened material, and as shown in Fig. 5, are embodied with the edge reinforcement, representing one form of strengthening the loops. The reinforcement shown in Fig. 5 may be molded separate, and then put around the body portion A, and the whole bag vulcanized together, treating the straps F so as to prevent their adhesion to the body of the bag.

In Fig. 7 the projection to surround the pendant and bow, is made as small as possible and in that form is adapted to put on watches arranged for a wrist chain to be attached to either side, and therefore has projections H, with small openings at the end, permitting the chain to be passed through and which will then cling close to the chain making the connection practically waterproof, although not as secure as the other forms. In this form, however, a little moisture leaking through the opening in H, through which the chain passes, would only come in contact with the side of the case, with practically no chance of its working its way between the case and bag to the crown, and therefore this form would practically be a waterproof protection to all intent and purpose.

Fig. 8 shows a bag in which a wrist strap of rubber or other suitable material is vulcanized or cemented against the back of the bag transversely, the bag proper thereby being as compact as possible and simply large enough to fully inclose case, pendant, crown and bow.

It will thus be seen that my invention involves the production of an article of manufacture which can be made from molds or dies into any desired shape, but primarily to be a snug fit around the case and the contiguous material, preferably rubber, inclosing the pendant and crown so as to prevent any moisture or water from entry through the aperture surrounding the crown, while also preventing leakage through any of the joints in the case. The face of the bag having an opening smaller than the case, must be so arranged that the case may be inserted through the opening, which, in my preferred form is accomplished by having the face of rubber, which will stretch sufficiently to permit this. In some forms it may be practical to have the back of leather or other material tougher than rubber as it is not necessary for that to stretch. Various modifications

may be made to strengthen the bag and still leave in the entire article the embodiment of the essential features of my invention.

The figures D on the face of the bag may be formed in the molds as recesses, so as to stand out on the rubber face,—or they may be made in any other manner so as to be clearly visible.

While I have shown particular embodiments in the drawings herewith and described these, various modifications are permissible without departing from the spirit of my invention, but what I claim and desire to secure by Letters Patent is:

1. A waterproof watch bag comprising a body portion hermetically inclosing the case, pendant and crown, and having an opening on one side smaller than the crystal of the watch with a substantial annular surface surrounding the opening adapted to form a surface contact with the crystal, and the material of the face of the bag surrounding said opening being adapted to distort to an extent to permit the insertion of the watch case, and a beading integral with the edge of said opening.

2. A waterproof watch bag consisting of a continuous casing completely surrounding the case, pendant and crown, an opening on one face of the bag over the middle of the dial and through which the hands are visible, a circular beading concentric with the opening of the bag, and loops attached to the back of said bag adapted to engage a securing strap.

3. A waterproof watch bag comprising a continuous rubber casing conforming to the shape and inclosing the case, pendant and crown, a reinforcing member surrounding the periphery of the case, a flexible portion between the periphery and on one side having an opening with a reinforced edge, two loops forming an integral part of the back of said bag forming two narrow slots adapted to receive a strap, for the purpose described.

4. A waterproof watch bag comprising a continuous rubber casing conforming to the case, pendant and crown, adapted to snugly encircle the same, an opening through one side of said casing, and an edge on said opening adapted to form a sealed surface contact on the crystal of the watch.

5. A waterproof watch bag comprising a continuous casing conforming snugly to the case, pendant and crown, an opening on one side of said casing and numerals surrounding said opening permanently embodied on said casing.

6. A waterproof watch bag comprising a casing conforming to and adapted to snugly fit a watch case, an integral projection on said casing adapted to accommodate the pendant and adjacent parts, an opening on

one side of said casing, numerals surrounding said opening and arranged thereon with relation to the projection on the casing, in the same relation as the numerals of a watch case bears to the pendant and the case.

7. A watch bag comprising a continuous rubber casing completely inclosing the case, pendant and crown, and adapted to closely conform to and engage the case back and 10 face, an aperture in the bag concentric with

the face side and having a reinforced edge bordering said opening and adapted to closely apply to and form a seal with the marginal surface of the crystal of a watch.

Signed at New York, this first day of 15 March, 1915.

LOUIS E. F. WACHTER.
